US0D1109240S

(12) **United States Design Patent** (10) **Patent No.:** **US D1,109,240 S**
(45) **Date of Patent:** **** Jan. 13, 2026**

(54) **GAMING MACHINE**

(71) Applicant: **Aristocrat Technologies, Inc.**, Las Vegas, NV (US)

(72) Inventor: **William Lamb**, Eagleville, TN (US)

(73) Assignee: **Aristocrat Technologies, Inc.**, Las Vegas, NV (US)

(**) Term: **15 Years**

(21) Appl. No.: **30/002,075**

(22) Filed: **May 1, 2025**

Related U.S. Application Data

(62) Division of application No. 29/854,171, filed on Sep. 22, 2022, now Pat. No. Des. 1,074,434, which is a division of application No. 29/727,552, filed on Mar. 11, 2020, now Pat. No. Des. 969,928.

(57) **CLAIM**

The ornamental design for a gaming machine as shown and described.

DESCRIPTION

FIG. 1 is a front perspective view of a gaming machine showing the claimed design;

FIG. 2 is a front elevation view thereof;

FIG. 3 is a rear elevation view thereof;

FIG. 4 is a right elevation view thereof;

FIG. 5 is a left elevation view thereof; and,

FIG. 6 is a top plan view thereof.

The dashed broken lines in the drawings illustrate portions of the gaming machine that form no part of the claimed design.

1 Claim, 6 Drawing Sheets
